UNITED STATES PATENT OFFICE.

JOHN R. LONG, OF AKRON, OHIO.

BENCH-VISE.

1,265,218.

Specification of Letters Patent. Patented May 7, 1918.

Application filed July 23, 1917. Serial No. 182,146.

To all whom it may concern:

Be it known that I, JOHN R. LONG, citizen of the United States, residing at Akron, in the county of Summit and State of Ohio, 5 have invented certain new and useful Improvements in Bench-Vises, of which the following is a specification.

This is an improvement in bench vises, substantially as shown and described and 10 particularly pointed out in the claims.

Figure 1 is a sectional elevation of the vise, taken on a line corresponding substantially to x, x Fig. 2. Fig. 2 is a cross-section on a line corresponding to 2—2, Fig. 1. Fig. 15 3 is a plan view with the jaws placed horizontally in the base instead of vertically therein as in Fig. 1, and as hereinafter fully described. Fig. 4 is a front end elevation of Fig. 3. Fig. 5 is a sectional detail on line 5, 20 Fig. 1, showing the square shank of the tubular nut for the operating screw. Fig. 6 is a detail of the said nut and Fig. 7 is a detail of the tightening collar.

In the present construction the jaws may 25 be set to any desired angle in either vertical or horizontal relations without the necessity of changing the position of the vise on the post or support, and the present improvement also provides for a powerful grip on 30 the post when the jaws are clamped, and which eliminates considerable past difficulty in these particulars.

The provision herein for rotating the jaws to all degrees in either plane is es- 35 pecially emphasized, and differentiates the construction from anything shown in the foregoing patents or that is known to me in other vises. The present construction also insures absolutely parallel jaw-faces, 40 and remedies defects in my Patents Nos. 667,151 and 1,196,560, particularly the tendency in the outer jaw to grip tighter at the top than at the bottom. This objection is impossible in the present vise, as hereinafter 45 more fully set forth.

These comparisons serve in a measure to show the mechanical and operating differences and advantages herein over the prior 50 patents, notwithstanding that certain of the parts here and there bear structural resem- blances to like parts in the said patents. Thus, the base b is adapted to be removably bolted or screwed to a suitable support and is provided with a preferably hollow cylin- 55 drical post 2 of suitable elevation substan- tially as in Patent 1,196,560. But the uni-

tary yoke y , herein is provided with two bores, 3 and 4, at right angles to each other and adapted to engage rotarily and fit snugly over or upon the post 2 of the base 60 according as to whether a vertical or horizontal position of the jaws be wanted, Figs. 1 and 3, and in addition to this there is what may be termed a longitudinal bore or opening in and through which the jaw extensions 65 or shanks are mounted. Also, it will be noticed that the yoke y is split or slotted at 6 through the walls of both bores in such a manner that the said bores shall be compressible or contractible in sufficient measure to 70 clamp the same firmly upon the post 2 when definite locking of the jaws in any adjusted position is desirable for a given work. This of course contemplates rotation of the jaws in the yoke to get the desired angle and then 75 locking the jaws in such position by the means provided for this purpose.

The said means involve the two jaw mem- 80 bers J and J' , each of which has a tubular shank or extension 8 and 9 respectively, pro- jected into the coaxial openings through the front and rear wings of the yoke relatively 85 above the said bores, the shank 8 of the inner jaw J having its bearings immediately within the said openings, while the shank 9 90 has its bearings within the hollow shank of the said inner jaw and terminates just with- in the flanged or partially closed end 10 thereof.

The shank or stem 8 of the inner jaw is 90 cylindrical and tubular and adapted to be rotated in its bearings in the yoke, and has an internal rectangular bearing 12 adapted to receive the correspondingly shaped shank or extension 9 of the outer jaw. The said 95 jaw 9 is therefore slidable lengthwise in the said bearing but not rotatable independently of the inner jaw. This serves to keep the two jaw faces in opposite working relations at all times at whatever angle they may 100 occupy in the yoke. In addition to the angular close-fitting bearing 12 the inner jaw also provides a support 13 at its front for the outer jaw, and altogether the said jaws are so related and mutually supported that posi- 105 tively parallel jaw-faces are maintained at all times however near or far apart they may be in engaging the work. Emphasis is laid on this feature because it lies at the bottom of the present invention.

Now, as further material details, it will 110 be observed that the operating screws s

engages in a tubular nut n , which has an annular bead or flange 15 bearing outwardly against the otherwise closed or flanged end 10 of inner jaw shank 8, and that said nut has a square shank 16 immediately outside said flange engaged through a correspondingly square or angular hole through said otherwise closed end 10. The outer end of nut n is screw threaded to receive a nut 18 thereon, and a disk shaped collar c , Fig. 7, has a square hole through its center engaged upon the said shank 16 and seated about its inner recessed edge against the edge of the yoke.

15 It will be noticed that a definite but limited space is provided for between said collar and the end 10 of the inner jaw, which stops short of the outer edge portion of the yoke, engaged by said collar, and the jaw J 20 has an annular shoulder 14 which engages against the edge of the forward portion or wing of the yoke. It follows, of course, when the nut 18 is tightened, that a pull will be exerted by the flange 15 on inner jaw shank 8 and corresponding inward pressure against the yoke by collar c , and having the yoke slotted at 6 through the walls of the bores 3 and 4, thereof, it follows that there must be a clamping effect exerted on the front and 25 rear wings of the yoke toward each other and which will close the bore that may be in use at the time tightly upon post 2 and lock the vise against rotation thereon. Otherwise, or when nut 18 is loosened, the vise 30 may be rotated or turned to any preferred angle, but the clamping of the jaws is independent of this operation and through screw s . Notice that the yoke is provided with an opening between its wings, or front and 35 rear, down to the said slot 6.

40 A bushing 20 fixed in the outer jaw serves as a bearing for the operating screw, and a collar 21 pinned on the screw bears against said bushing and confines the screw in working relations in said jaw. The head 22 of said screw which carries the handle rod h bears directly against the outside of the jaw.

45 From the foregoing description and as compared especially with my Patent No. 1,218,788, it will be seen that the invention herein resides primarily in the unitary or one piece yoke as compared with the sectional or two piece yoke in the said patent, and the net result is to get uniform and exact gripping over the entire surface and depth of the jaws, whereas in Patent 50 1,196,560 the outer jaw tends to always grip the work tighter at the top than lower down in the jaws and which is a serious defect 55 which has been overcome in the present construction.

60 The opening or recess 6 transversely down into the yoke of course is necessary to obtain the clamping effect upon post 2 when the 65 ends or wings w and w' on either side of

said recess are drawn toward each other. The said yoke is of cast metal, but with the central recess between the wings and the opening by slot 6 into the bores 3 and 4, there is sufficient spring in the remaining metal about the outer walls of said bores to effect clamping upon post 2. Of course in any case the said bores 3 and 4 fit quite snugly upon the post so that a comparatively slight compression will make the clamping secure, and hence, also, there is no unfavorable effect transmitted to the jaws.

What I claim is:

1. In bench vises, a base, a unitary yoke having dual bores at an angle to each other adapted to be engaged on the base and provided with wings having a recess between the same and a slot from said recess through the adjacent walls of said bores, in combination with jaws having portions engaged in said wings and a tightening screw adapted to lock said jaws upon the yoke and the yoke upon the base.

2. In bench vises, a base with a post, a unitary yoke having a plurality of bores at right angles to each other to support the same on said post at different angles and wings spaced apart by a recess between the same across the body thereof and provided with a slot at its bottom open to the said plurality of bores and jaws having extensions and a screw extending through said wings and adapted to draw the same toward each other and more or less close said slot and bind the yoke on said post and the jaws together.

3. In bench vises, a unitary yoke having front and rear wings provided with co-axial annular openings through the same and a plurality of bores relatively at one side thereof in the base of the yoke, and said yoke having a recess across the middle thereof between said wings extending across the bottom plane of said openings and a slot from the bottom of said recess into the said bores.

4. In bench vises, a yoke and a pair of jaws operatively engaged therein and provided with shanks interlocked between their ends against separate rotation, the inner of said shanks being angular in cross section and the outer shank having an angular bearing in which the inner shank is slidably mounted and a screw to lock said jaws together upon said yoke.

5. In bench vises, a unitary yoke having front and rear wings and constructed to draw said wings toward each other, in combination with an outer jaw having a shank rotatable in said yoke and provided with an angular internal bearing, an inner jaw having an angular shank slidably mounted in said bearing and clamping means comprising an operating screw engaging the ends of said outer shank against opposite sides of said wings.

6. In bench vises, a yoke having a plurality of bores to engage upon a support and front and rear wings with an open recess between them and an open slot at the bottom of said recess into said bores, in combination with jaws having shanks operatively supported in said wings and clamping means engaging the outer of said shanks upon said

wings and adapted to draw the wings toward each other and thereby lock the yoke 10 upon its support and the jaws on the yoke.

Signed at Cleveland, in the county of Cuyahoga, and State of Ohio, this 7th day of July, 1917.

JOHN R. LONG.
